HUGO E. GRIESHABER, OF NEW LONDON, CONNECTICUT, ASSIGNOR TO ELECTRIC BOAT COMPANY, OF GROTON, CONNECTICUT, A CORPORATION OF NEW JERSEY

MINE-LAYING SUBMARINE

Application filed January 19, 1929. Serial No. 333,609.

This invention relates to submarine boats for laying mines, and more particularly to a boat for laying mines by what is known as the wet mine system.

One of the main objects of my invention is to provide a boat in which the mine stowage and discharge means are so constructed and arranged as to conserve the valuable space in the pressure hull while not necessitating any increase in the dimensions of the boat. Another object is to provide means whereby a multiplicity of closures and complicated mechanism for discharging the mines is avoided. A further object is to provide means whereby the mines are discharged laterally of the hull so as to be clear of the propeller.

A still further object is to provide means for discharging the mines, so constructed and arranged that eddies such as would have detrimental effects on the speed and radius of action of the boat are avoided. It is also an object of my invention to provide mine stowage and discharge means so related to the hull as to assure proper trim of the boat at all times and facilitate compensation for the mines discharged.

Further objects and advantages of my invention will appear from the detailed description.

In the drawings:

Fig. 1 is a longitudinal vertical sectional view through the mid-ship portion of a submarine constructed in accordance with my invention;

Fig. 2 is a horizontal sectional view through the mid-ship portion of the boat, partly in plan;

Fig. 3 is a section taken substantially on line 3—3 of Fig. 1;

Fig. 4 is a section taken substantially on line 4—4 of Fig. 1;

Fig. 5 is a section taken substantially on line 5—5 of Fig. 1;

Fig. 6 is a section taken substantially on line 6—6 of Fig. 1.

The drawings are, in the main, diagrammatic and all unnecessary parts have been omitted for clearness of illustration.

The boat comprises an inner pressure resisting hull 1 and an outer hull 2, the space between these two hulls constituting ballast and compensating tanks in a known manner. Between the hulls 1 and 2, and at each side thereof, I provide two mine stowage tubes 3, these tubes extending fore and aft of the hull at the mid-ship portion thereof. The tubes 3 are preferably horizontal, as illustrated, though this is not essential under all conditions and the tubes may be inclined if necessary or desired. At their forward ends the tubes open into a vertical stack 4 which opens through the outer hull 2 at the upper portion thereof. The upper end of this stack is normally closed by a hatch cover or door 4a. The after end of each of the tubes is open and is in direct communication with a space 5 in which is mounted a cradle or spoon 6 which is hinged or pivoted at 7 for movement toward and away from the inner hull 1. This spoon, when in its normal raised position, as in Fig. 3, is disposed substantially flush with the outer face of hull 2 so as to form a continuation thereof. The members 6 serve to normally substantially close the space 5 and the hull 2 is faired to these members. This is advantageous as avoiding objectionable eddies such as would be apt to interfere with the speed or radius of action of the boat. The tubes 3 are open to the sea through the spaces 5 at their after ends, but these tubes are water-tight and are out of communication with the ballast tanks in which the tubes are located.

The spoons 6 are operated by piston rods 8 which extend through stuffing boxes 9 in the inner hull 1. These piston rods are connected to pistons which operate in cylinders

10 suitably mounted in a mine room or compartment 11 within hull 1. By admitting compressed air into cylinders 10 at opposite sides of the pistons therein, the spoons can 5 be operated for discharging the mines as desired. Normally, the spoons 6 are held in inoperative position as illustrated in Fig.

3. These spoons are disposed in alignment with and closely adjacent the after ends of 10 the tubes 3, when in normal or inoperative position, to receive mines discharged from these tubes.

Each of the tubes 3 has associated therewith suitable conveyor means for moving 15 the mines through the tubes. Conveyor means of this type is known in the art and need not be illustrated nor described in detail. Briefly, a plurality of shafts 12 extend into the lower portion of each of the 20 tubes 3. These shafts carry sprocket wheels or pinions 13 at their outer ends, being provided at their inner ends with sprocket wheels about which pass sprocket chains 14, these chains also passing about a sprocket 25 wheel secured on a shaft 15 driven by an electric motor 16 within the mine room 11, suitable switch means being provided in the mine room for controlling the operation of this motor. The pinions 13 mesh with racks 30 14a carried by the mines 15a which are stowed in tubes 3. A conveyor structure of this general type is disclosed in my patent for Mine discharging device, issued October 27, 1925, Patent No. 1,558,868.

25 In shipping the mines, the hatch door or cover 4a being opened, the mines 15a are lowered into the stack 4, as indicated in Fig. 1, and are moved forwardly through the lower tube until this tube has been completely filled, one mine remaining in the bottom of stack 4. A suitable spacer is then placed above this mine and the mines are loaded into the upper tube 3, in the same manner, until this tube is filled, the 40 last mine loaded or shipped remaining in stack 4. A suitable spacing member is then placed between this mine and the hatch cover 4a, which is then suitably secured closed so as to effect a proper closure of 45 the stack 4. The mines are held against casual discharge from the after ends of the tubes by stop pins 17 which operate through stuffing boxes 18 extending into the mine room, these pins projecting outwardly across 50 the ends of the tubes as in Fig. 4.

When it is desired to discharge or lay the mines, the motors 16 are set into operation so as to drive the shafts 12, suitable clutch means being provided, if desired, to control 55 operation of the conveyor without necessitating stoppage of the motor. This result can also be obtained by a suitable switch in the mine room controlling the motor circuit. The stop pins 17 are, of course, with- 60 drawn before setting the conveyor mech-

anism into operation. The conveyor mechanism serves to move the mines aft in the tubes 3, each mine, as it leaves the tube, passing into the spoon 6. When the mine is in full position upon the spoon, it engages 70 a contact member 19 at the after end of the space 5.

This member has associated therewith suitable means, either electrical or mechanical, for operating a valve which admits 75 compressed air to the cylinder 10 at the inner side of the piston. This serves to project rod 8 thus swinging the spoon 6 outwardly into the position indicated by dotted lines in Fig. 3, thus discharging the 80 mine laterally of the hull and clear of the side thereof. The mine is thus discharged out of the path of the propeller. In practice, a mine is first discharged from one of the lower tubes, a second mine being then 85 discharged from the lower tube on the opposite side of the hull, a third mine being discharged from the top tube at the side of the hull at which the first mine was discharged, and the fourth mine being discharged from the top tube at the side of the 90 hull from which the second mine was discharged, this order being repeated until all of the mines have been discharged from the tubes. It is not essential that the mines be 95 discharged in this particular order, though it is the order which I prefer as maintaining proper trim of the boat at all times.

Compensating tanks 20 and 21 are provided adjacent space 5 and stack 4, respectively, these tanks being at the ends of the ballast tanks 22 in which the tubes 3 are disposed. Whenever a mine is discharged a suitable quantity of water is taken into the tank 20 to compensate for the mine, and as the succeeding mine is moved aft in the tube 3, water is caused to flow forward from tank 20 to tank 21, in a known manner, to offset the after moment due to movement of the mine aft.

When all of the mines have been discharged, both of the compensating tanks 20 and 21 are full of water, these tanks being of proper capacity to compensate for the mines. I have shown the tubes, including the stack 4, as of proper length to afford stowage for ten mines each, making a total of forty mines which can be carried and discharged from these tubes. The length of the tubes may, however, be varied within 110 limits, and I do not in any way intend to limit myself to the number of mines stowed in the tubes. It is particularly noted that the tubes are disposed at the mid-ship portion of the boat at opposite sides thereof and that the compensating tanks 20 and 21 are adjacent the ends of these tubes. This assures proper trim of the boat and facilitates 115 compensation.

120 Preferably the mine stowage tubes are at 130

the midship portion of the boat, though this is not essential. In its broader aspects, my invention comprehends any suitable arrangement of the tubes relative to each other and to the hull, by which valuable space within the pressure hull is conserved and a multiplicity of closures for the tubes, and associated complicated operating and control mechanisms, are avoided.

10 What I claim is:—

1. In a mine laying submarine boat, an outer hull and an inner hull, tubes between the two hulls and disposed fore and aft thereof, said tubes being adapted for reception of mines and means operable from within the hull for discharging mines from said tubes laterally of and outwardly beyond said hull.

2. In a mine laying submarine boat, an outer hull and an inner hull, horizontal tubes between the hulls and adapted for reception of mines, and means for discharging the mines for said tubes, said means including a contact member disposed for contact by a mine positioned in said discharge means for discharge thereby.

3. In a mine laying submarine, a tube extending fore and aft of the hull and adapted for reception of a plurality of mines, a member disposed to receive a mine moved outwardly beyond the tube, said member being mounted to discharge the mine into the sea when moved into operative position, and means for operating the mine receiving member comprising a contact member disposed for contact by a mine which has been properly positioned upon said member.

4. In a mine laying submarine boat, an outer hull and an inner hull, a mine stowage tube between the hulls and extending fore and aft thereof, the inner hull comprising a mine room, a member at the outlet end of the tube and normally disposed to receive mines moved outwardly therethrough, said member being movable into position outwardly beyond the hull to discharge the mine therefrom, means operable from within the mine room for advancing the mines in the tube toward the outlet end thereof, and means operable from within the mine room for operating the mine receiving and discharging member.

5. In a mine laying submarine boat, an outer hull and an inner hull, a mine stowage tube between the hulls and extending fore and aft thereof, the inner hull comprising a mine room, a member at the outlet end of the tube and normally disposed to receive mines moved outwardly therethrough, said member being movable into position to discharge the mine therefrom, means operable from within the mine room for advancing the mines in the tube toward the outlet end thereof, means operable from within the

mine room for operating the mine receiving and discharging member, and a contact member disposed for contact by a mine properly positioned upon the receiving and discharging member.

6. In a mine laying submarine boat, a tube extending fore and aft of the hull at the side thereof and having its outlet end directed aft, said tube being open to the sea through its outlet end, means for advancing the mines in the tube toward the outlet end thereof, and means operable from within the hull for receiving the mines from the tube and for discharging them into the sea.

7. In a mine laying submarine boat, a tube extending fore and aft of the hull at the side thereof and having its outlet end directed aft, said tube being open to the sea through its outlet end, means for advancing the mines in the tube toward the outlet end thereof, and means operable from within the hull for receiving the mines from the tube and for discharging them into the sea outwardly beyond the side of the hull.

8. In a mine laying submarine boat comprising a mine room within the pressure hull and located amidship, a mine stowage tube extending fore and aft of the hull with its outlet end in the plane of the mine room, means controlled from the mine room for advancing the mines in the tube toward the outlet end thereof, and means operable from within the hull for receiving the mines from the tube and for discharging them into the sea.

9. In a mine laying submarine boat comprising an outer hull, an inner pressure hull, and a midship mine room, a mine stowage tube between the hulls at the side thereof and extending fore and aft of the boat, the outlet end of the tube being open to the sea and in the plane of the room, means controlled from the mine room for advancing the mines in the tube toward the outlet end thereof, and means operable from within the hull for receiving the mines from the tube and for discharging them into the sea.

10. In a mine laying submarine boat, a mine stowage tube, means operable from within the hull for receiving mines from the tube and for discharging them into the sea outwardly beyond the side of the hull structure, and means for transferring the mines from said tube to the receiving and discharging means.

11. In a mine laying submarine boat, mine stowage means, a mine receiving and discharge member operable from within the hull and disposed to discharge mines into the sea and outwardly beyond the side of the hull structure, and means for transferring the mines from said stowage means to said member.

12. In a mine laying submarine boat, an inner hull and an outer hull provided with a mine discharge opening, and a mine receiving and discharge member disposed to close said opening when in receiving position, said member when in discharging position being disposed to discharge a mine therefrom into the sea and outwardly beyond the side of the outer hull, the receiving and discharge member being operable from within the hull.

In witness whereof, I hereunto subscribe my name this 7 day of January, 1929.

HUGO E. GRIESHABER.
